WIRE HOLDER

Edwin M. Meyer, Parkersburg, W. Va., assignor to
 Porcelain Products, Inc., Findlay, Ohio, a corporation of Delaware

Application November 29, 1938, Serial No. 243,035

4 Claims. (Cl. 174—165)

This invention relates to insulators and more particularly to the type known as wire holders in which a hole extends transversely through the body portion to receive an electric wire. Such insulators are generally used where wires are brought in from a transmission line to a building or the like. Such wiring imposes considerable tension upon the insulator and its support particularly in the direction of the longitudinal axis of the insulator. My invention is not limited, however, to the specific purpose of "dead-ending" wires as it is well adapted to be used as a support for electrical wiring within buildings, on poles, and in various other places. Insulators of this type are customarily made of porcelain, although other materials may be used, and it is desirable to utilize the maximum strength of porcelain which is only developed when it is placed under compression rather than tension. The present invention provides an insulator which is more resistant to dislodgment when in use and also provides means by which the material of the insulator where it holds the conductor is itself placed under compression with the consequent increase in strength.

One of the objects of my invention is to provide an insulator with improved supporting structure for resisting stress incidental to the use of the insulator.

Another object of my invention is to provide improved means for attaching the wood screw to the body of the insulator.

A further object of my invention is to provide a structure which prevents localized torsion or other stress on portions of the porcelain insulating body during attachment of the insulator to a supporting structure such as a building, pole or the like.

The above objects are obtained by the design of a structure in which the porcelain insulator body is maintained under compression between a yoke and a cross beam or strut in which latter the main web is parallel to the direction of the load and thus will have a larger section modulus resulting in maximum strength and stiffness. The yoke itself places the porcelain under compression at the critical loading zone for maximum strength.

Other objects and advantages will be apparent from the following description of the preferred form of my invention as illustrated in the drawings in which:

Fig. 1 is a side elevation of the improved insulator, shown partly in section;

Fig. 2 is a side view partly in vertical section, on the line 2—2 of Fig. 1;

Fig. 3 is a plan view of the base of the insulator;

5 Fig. 4 is an exploded perspective view of the attaching strap and cross member;

Fig. 5 is a side elevation of a modified form of insulator, partly in vertical section on the line 5—5 of Fig. 6;

10 Fig. 6 is a side elevation of the insulator shown in Fig. 5;

Fig. 7 is a plan view of the base of the modified form, and

15 Fig. 8 is an exploded perspective view of the attaching strap and cross member used in the modified insulator.

For the purpose of illustrating the principles of this invention the drawings show characteristic forms in which 11 indicates the insulating

20 body member formed of a single piece of porcelain constituting a knob of the generally desired form having a flat circular base 12. This body member is generally glazed. The base of the body member is generally circular in form as shown in Fig. 3 except where there is a diametrical channel 13 intersecting the rim of the base. Centrally of the base and extending upwardly from the channel is a small recess 14 preferably circular for the purpose of receiving the head

25 of a lag screw or equivalent attaching member.

Transversely through the mid-portion of the body is a wire-receiving passageway 15. This is intended to carry the electric conductor and is of suitable form also to receive a tool such as

35 an ordinary screw driver by which the wire holder may be attached to its support.

It will be noted that the passageway 15 extends in a direction at right angles to that of the base channel 13. A second passageway 16 extends

40 transversely of the body above the wire-receiving passageway 15. This second passageway 16 is parallel to the base channel 13 and in the same vertical plane as indicated on Fig. 1.

The opposite sides of the body have parallel

45 grooves 17 extending vertically from the passageway 16 downwardly through the base and intersecting the base channel 13. The passageway 16 and the grooves 17 provide a saddle for a yoke 18. This yoke is in the form of a flat metal strap or the like and its ends extend into the base channel 13.

The base channel is adapted to carry a suitable cross beam or strut. As shown in Figs. 1 to 4 inclusive this strut is in the form of an inverted box 19. The upper portion or bottom 20 of the

strut rests against the body. There is a peripheral flange 21 extending around this bottom 20 and downwardly toward the base of the body. This flange or web 21 extends in a vertical direction or longitudinally with respect to the porcelain body and the attaching means. It thus provides a maximum of strength and stiffness. The bottom 20 has an opening 22 shown in this instance to be square. This opening is intended to receive the attaching screw 23, the shank 24 of which has a square form corresponding to the opening 22. The head 25 of the screw is generally round and loosely received within the recess 14.

The ends 26 of the yoke 18 are bent inwardly and up within the web 21 in the manner indicated in Fig. 2. The yoke 18 thus serves to clamp the insulating body 11 to the strut 19 with considerable compression. Due to the squared shank 24 of the screw the latter is constrained to rotate with the strut 19 and this in turn has an extended bearing surface between the web 21 and the adjacent side wall of the channel 13. It follows that the whole device is rigidly assembled and may be attached to a supporting structure, building, pole or the like with little risk of damage. In service, with the base 12 against the supporting structure, the strut 19 is free from the supporting structure but constantly drawn down by the screw head 14 thus maintaining tension upon the yoke 18. The ends 26 of the yoke fit within a recess 27 of the web 21 holding the strut firmly against rocking.

Referring to the modification shown in Figs. 5 to 8 inclusive the construction of the porcelain body 11 with its base 12; channel 13; recess 14 and passageways 15 and 16 is the same as above described.

The cross beam or strut in this form is made of two flat metal plates 28. These plates have wide webs 29 terminating in tongues 30. The mid-portion of the plates 29 are struck outwardly in an angular direction to form a square bore 31. This bore receives the square shank 24 of the screw 23.

The strut 28 in this form rests within the channel 13 with its webs 29 in a longitudinal direction as shown in Fig. 5.

The yoke 32 has the ends 33 extending to the far edge of the strut 28. A squared opening 34 is provided in each end 33 opposite the tongues 30, 30. The latter extend through the openings 34 and are struck outwardly as shown in Figs. 6 and 7. In this manner the yoke serves to clamp the body 11 against the strut 28 in the manner and for the purposes already described.

The wire holder when made in the forms above described is cheap to construct and extremely serviceable. Its electrical characteristics are satisfactory and the porcelain body maintained under compression in service so that maximum

strength results. The device is easily attached to a support by being driven against the latter and screwed into place with the base against the support and the strut and yoke under tension.

5 While I have shown and described the preferred embodiment of the invention it will be understood that various changes can be made in material and design without departing from the spirit of the invention as defined in the following claims.

What I claim is:

1. In an insulator, an insulating body having a base and a transverse wire-receiving passageway, a diametrical channel in the base, a second passageway transversely through the body parallel to said channel and above the wire-receiving passageway, a strut in extended contact with the base of said channel, said strut having a web extending longitudinally of the body and away from said transverse passageways, a strap passing through the second passageway and having its ends overlying and interlocked with said web and an attaching means carried by said strut.

2. In an insulator, an insulating body having a base and a transverse wire-receiving passageway, a diametrical channel in the base, a second passageway transversely through the body parallel to said channel and above the wire-receiving passageway, a strut in extended contact with the base of said channel, said strut having a downwardly extending flange at each end, a yoke passing through the second passageway and having its ends bent inwardly around said flanges, and an attaching means carried by said strut.

3. In an insulator, an insulating body having a base and a transverse wire-receiving passageway, a diametrical channel in the base, a second passageway transversely through the body parallel to said channel and above the wire-receiving passageway, a strut in said channel, said strut comprising two flat plates in face-to-face contact with spaced portions forming a central bore longitudinally of the insulating body, an attaching means carried in and rotatable with said bore, and a yoke passing through the second passageway and having its ends interlocked with said strut.

4. In an insulator, an insulating body having a base and a transverse wire-receiving passageway, a diametrical channel in the base, a second passageway transversely through the body parallel to said channel and above the wire-receiving passageway, a box shaped strut in said channel, said strut having a continuous downwardly extending peripheral flange, a yoke passing through the second passageway and having its ends bent inwardly around the opposite end of said flange, and an attaching means carried by said strut.

EDWIN M. MEYER.
